(57) **CLAIM**

I claim the ornamental design for an actuator bridge, as shown and described.

DESCRIPTION

FIG. 1 is a top perspective view of an actuator bridge of the present claimed design;

FIG. 2 is a top plan view of the actuator bridge shown in FIG. 1;

FIG. 3 is a longitudinal side elevation view of the actuator bridge shown in FIG. 1, the other longitudinal side elevation view being identical thereto;

FIG. 4 is a bottom plan view of the actuator bridge shown in FIG. 1; and,

FIG. 5 is a latitudinal side elevation view of the actuator bridge shown in FIG. 1, the other latitudinal side elevation view being identical thereto.

Features shown in broken lines in the drawing form no part of the claimed design.
